UNITED STATES PATENT OFFICE.

DAVIS S. STOVER, OF AMSTERDAM, NEW YORK.

TUBE-CLEANER.

1,174,198.

Specification of Letters Patent.

Patented Mar. 7, 1916.

Application filed December 26, 1914. Serial No. 879,047.

To all whom it may concern:

Be it known that I, DAVIS S. STOVER, a citizen of the United States, residing in Amsterdam, county of Montgomery, State 5 of New York, have invented certain new and useful Improvements in Tube-Cleaner's; and I do hereby declare the following to be a full, clear, and exact description of the invention, such as will enable others skilled 10 in the art to which it appertains to make and use the same.

This invention is directed to the provision of an improved form of apparatus for cleaning the interior of tubes adapted particularly for use in cleaning the tubes of 15 boilers.

The object of the invention is to provide a tube cleaner for this use which may be readily manipulated for performing the 20 cleaning operation conveniently and rapidly, with which the cleaning operation is performed from one end of a boiler only, which may be used even when the space in front of the boiler is restricted and which 25 is of simple construction adapting it for manufacture at low cost.

The invention is preferably embodied in a cleaner of the type comprising a tubular frame adapted to be applied to one end of 30 a boiler tube, a strip or similar power transmitting member passing through the frame, a cleaning tool on the end of the strip and operating devices mounted on the frame for imparting a reciprocatory motion to the 35 strip and the tool attached thereto, the parts being so constructed that the requisite power can be transmitted to the strip and tool when they are moving in either direction so that the tool will clean while moving in 40 both directions and while located at any point throughout the length of the tube.

One of the features of the invention relates to the construction of the power transmitting member extending from the operating 45 devices to the tool. The construction of this member is such that it may flex readily in one direction but not in the other. It has been proposed heretofore to employ a power transmitting member in the 50 form of a flexible metallic strip carrying the tool at one end and coacting with the operating devices at a point distant from the tool. I have found that when such a strip is employed, efficient operation is difficult 55 or impossible because of the flexure of the strip, particularly when the tool has been

moved a substantial distance into a tube. In accordance with this invention, the power transmitting strip is so made that it can flex in one lateral direction but not in the other. 60 When so made, the strip cannot flex so as to contact with opposite sides of a tube at a plurality of points along the length of the tube, particularly when the tool has been moved into a tube a substantial distance, as has been the case with the forms of power transmitting strips heretofore proposed. Preferably, I employ a strip of sheet metal which possesses the requisite degree of flexibility and I apply to this a 70 multiplicity of metallic devices which project laterally from the strip on one side of the latter and which abut along their adjacent edges. Such pieces applied to the strip permit flexure of the strip in one lateral 75 direction accompanied by separation of the adjacent edges of the pieces but preclude flexure in the opposite direction. As a result, the reciprocatory movement of the strip in the tube is not impeded to any substantial extent, less power is required to reciprocate the tool in the tube because of 80 the absence of a wedging effect of the strip in the tube and the apparatus can be used for cleaning the interior of tubes of greater 85 length because of the marked decrease in the amount of power required to reciprocate the tool.

Another feature of the invention resides in the construction of the devices whereby 90 the cleaning apparatus is applied to the end of a tube to be cleaned and gripped to the tube so that it will be held rigidly throughout the cleaning operation. These devices include certain expandible members 95 adapted to fit within the end of a tube and operating mechanism whereby they may be expanded into gripping relation to the interior walls of the tube.

These and other features of the invention 100 will be better understood by reference to the following description taken in connection with the accompanying drawings, which show the preferred embodiment of the invention.

In the drawings, Figure 1 is an elevation of the apparatus, Fig. 2 is a longitudinal section thereof, Fig. 3 is a detail view of the power transmitting member, Fig. 4 is a transverse section on line 4-4 of Fig. 110 2, and Fig. 5 is a detail view in section showing a modification.

Referring to these drawings, the parts of the apparatus are assembled upon a tubular frame consisting of a tube 6 and a casting 7 secured to one end of tube 6. This casting 7 has a supporting handle 8 formed integral therewith by which the cleaner is manipulated. A power transmitting strip passes through the tubular frame and is adapted to be reciprocated by any suitable mechanism actuated either by power or by hand. In the present instance, I have shown the operating mechanism as consisting of a gear 9 pivotally mounted upon the casting 7 and having a handle 10 secured thereto, the teeth of this gear being adapted to coact with the power transmitting strip so as to reciprocate the same. At its end the power transmitting strip has a cleaning tool 11 secured thereto, this tool being of the usual 20 or any suitable construction.

For mounting the cleaner in co-operative relation to a tube to be cleaned, a collar 12 is slidably mounted upon the tube 6. This collar is provided with a tapered surface as shown in Figs. 1 and 2. In the collar 12 are a plurality of grooves, each of which receives one end of a flexible metallic strip 13 of spring metal. The several strips 13 extend parallel to the tube 6 and at their opposite ends bear upon the tapered exterior surface of a cam 14 in the form of a collar secured to the tube 6 adjacent to the end of the latter. The ends of the strips 13 are formed to present inclined surfaces which 35 conform closely to the shape of the surface of the collar 14. On the outer sides of these ends of the strips 13 their surfaces are substantially parallel to the axis of the tube 6 so that pads or engaging surfaces 15 are provided adapted to engage the interior wall of a tube. The strips 13 and the slideable collar 12 are reciprocated by means of an operating handle 16 which is pivotally mounted upon an extension 17 of the casting 7. This handle 16 is connected to the collar 12 by connecting rods 18, these being pivotally connected to the handle 16 at a point above the pivot of the handle.

The power transmitting strip by which 50 reciprocatory motion is transmitted from the gear 9 to the tool 11 consists of a long flexible metallic strip 19 provided with means for preventing flexure in one direction. For this purpose the strip 19 has a 55 plurality of metallic plates 20 applied thereto, each of which plates projects laterally from the strip 19 in one direction, the edges of the projecting parts of adjacent pieces 20 being in engagement. In Figs. 1 to 4 inclusive the pieces 20 are shown as made from short strips of sheet metal, each having its ends carried around the lateral edges of the strip 19, as shown at 21 in Fig. 4. Between its ends, each piece 20 is bent so as to provide a portion 22, which lies at a substantial

distance from the strip 19. The edges of the portions 22 of adjacent pieces 20 are in engagement as shown in Figs. 2 and 3.

In assembling the parts of the power transmitting mechanism, the tool 11 is secured to the strip 19 by any suitable means, such as the rivets shown at 23. A multiplicity of the pieces 20 are then applied to the strip 19 in the manner indicated in Fig. 4 and are moved along upon the strip until the end one abuts against the tool or the securing means 23 thereof. After the requisite number of pieces 20 have been applied to the strip, the extreme end of the strip is secured to a threaded bolt 24. The pressure member 25 is then passed over the bolt 24 and moved into engagement with the end piece 20. Then a nut 26 is screwed upon the bolt 24 so as to press the member 25 against the end piece 20 and thus force all of the pieces 20 into hard engagement. As shown in Fig. 4, the pieces 20 leave one side of the strip 19 exposed so that the teeth of the gear 9 may coact freely with a series of openings provided in the strip 19 to impart the desired reciprocatory movement to the strip and tool.

In Fig. 5 a slight modification of the construction shown in the other figures is illustrated. Here the pieces applied to the strip 19 are of a different shape. The body of the piece 27 is bent around the strip 19 and the ends 28 thereof are turned upwardly at a right angle to the strip 19 so that the projecting ends 28 of adjacent pieces 27 will 95 abut against each other and arrest flexure of strip 19 in one direction. In using this form of cleaning apparatus the tool and the end of the tube 6 are inserted in the tube to be cleaned until the tapered surface of the 100 collar 12 engages the end of the tube and wedges therein. The operator then grasps the handle 16 in one hand while holding the handle 8 in the other and presses forward on the former while pulling backward on the latter. In this way the collar 12 is forced into the end of the tube and at the same time the collar 14 is moved outwardly, the 105 tube 6 passing through the collar 12. This movement of the collar 14 relative to the 110 collar 12 and the strips 13 held by the collar 12, causes the ends of the strips 13 to be moved outwardly by reason of the cam action of the tapered surface of the collar 14 upon the coacting ends of the strips 13. 115 Thus the ends of strips 13 are forced outwardly or expanded into hard gripping relation to the tube and the cleaner is thus gripped to the tube with a high degree of 120 rigidity. The operator then turns the 125 handle 10 back and forth so as to impart a reciprocatory movement to the strip 19 and the tool 11 by reason of the coaction of the teeth of gear 9 with the openings in the strip. The tool 11 is thus reciprocated with 130

in the tube and a substantial degree of power may be applied to it while moving it in either direction. When the tool has been moved a substantial distance from the 5 frame, the transmission of reciprocatory motion to the tool through the strip 19 is accompanied by a tendency of the strip to flex. However, the pieces 20 applied to the strip 19 preclude flexure of the latter in one 10 direction. As a result the strip cannot flex so as to contact with opposite walls of the tube at a plurality of points along the length of the tube in which case the transmission of reciprocatory motion to the tool would be 15 difficult. At the same time, the power transmitting strip has a capacity for such flexure as will permit of using the apparatus even when the tubes of the boiler are of substantial length and the space in front of the 20 boiler is restricted.

What I claim is:

1. A tube cleaner comprising the combination of a frame adapted to be applied to the end of the tube, a power transmitting 25 member extending through the frame and beyond the same, a tool on the end of said member adapted to be reciprocated within the tube, operating devices on the frame co-operating with said member for reciprocating the member and the tool secured thereto, said member being capable of flexure in one direction at a multiplicity of points distributed throughout its length, and means for limiting flexure of the member in the 35 opposite direction at all points throughout its length; substantially as described.

2. A tube cleaner comprising the combination of a frame, a continuous flexible metallic strip extending therethrough, means 40 for precluding flexure of the strip in one direction while permitting flexure in the other direction, a tool secured upon one end of the strip and operating devices coacting with the strip to impart reciprocatory motion to the strip and the tool thereon; substantially as described.

3. A tube cleaner comprising the combination of a frame, a flexible metallic strip passing therethrough, a plurality of disconnected devices applied to the strip and having their adjacent edges abutting to arrest flexure of the strip in one direction, a tool secured to the end of the strip and operating devices on the frame for reciprocating the 55 strip and the tool secured thereto; substantially as described.

4. A tube cleaner comprising the combination of a frame, a flexible metallic strip passing therethrough, a multiplicity of 60 disconnected metallic plates applied to the strip each bent to provide a portion lying at a distance from the strip and the said portions

of adjacent pieces having their edges abutting, a tool secured upon the end of the strip and operating devices mounted on the frame 65 and engaging the strip to reciprocate the same and the tool secured thereto; substantially as described.

5. A tube cleaner comprising the combination of a frame, a power transmitting 70 member extending therethrough, means for reciprocating said member, a tool secured to the end of the member, a collar slidably mounted upon the frame, means for moving the collar upon the frame, expandible gripping members connected to the collar and means for expanding said members mounted upon the frame; substantially as described.

6. A tube cleaner comprising the combination of a tubular frame, a reciprocatory 80 member extending therethrough, a tool secured to the end of the member, a collar slidably mounted upon the frame and having a tapered exterior surface, means for moving the collar upon the frame, a collar 85 secured to the frame and having a tapered exterior surface and gripping members for engagement with the interior of a tube secured to said slide collar and engaging the tapered surface of the collar upon the 90 tube, substantially as described.

7. A tube cleaner comprising the combination of a frame, a power transmitting strip passing therethrough, a tool on the end of said strip, a collar mounted to slide 95 upon the frame and adapted to engage a tube, expandible gripping members for gripping the interior of a tube and means operated by movement of said collar lengthwise of the frame for moving said gripping members radially into engagement with the interior wall of a surrounding tube, substantially as described.

8. In a tube cleaner, a tool, a continuous flexible metallic strip connected to the tool 105 for operating it and means applied to the strip for limiting flexure of the strip in one direction while permitting it to flex freely in the opposite direction at a multiplicity of points throughout its length; substantially 110 as described.

9. In a tube cleaner, a tool, a continuous flexible metallic strip connected to the tool for operating it, and means applied to the strip for precluding flexure of the strip in 115 one direction while leaving it free in the opposite direction.

In testimony whereof I affix my signature in presence of two witnesses.

DAVIS S. STOVER.

Witnesses:

EDWARD A. McCAFFREY,
KATHERINE M. KAVANAGH.

It is hereby certified that in Letters Patent No. 1,174,198, granted March 7, 1916, upon the application of Davis S. Stover, of Amsterdam, New York, for an improvement in "Tube-Cleaners," an error appears in the printed specification requiring correction as follows: Page 3, line 116, claim 9, after the word "free" insert the words *to flex*; and that the said Letters Patent should be read with this correction therein that the same may conform to the record of the case in the Patent Office.

Signed and sealed this 28th day of March, A. D., 1916.

[SEAL.]

J. T. NEWTON,

Acting Commissioner of Patents.
